(57) **CLAIM**

The ornamental design for a pocket on shoe, as shown and described.

DESCRIPTION

FIG. 1 is a front perspective view of a shoe showing a new pocket design;

FIG. 2 is a side view thereof; and,

FIG. 3 is a side view of a second embodiment of the new pocket design shown in FIG. 1.

The broken line showing of the sole, portions of the upper, portions of the shoe, and zipper pull is for illustrative purposes only and forms no part of the claimed design.

The zipper teeth, shown in solid lines for clarity, are for illustrative purposes only and form no part of the claimed design.

1 Claim, 3 Drawing Sheets

FIG. 1

FIG. 2

FIG. 3
